(57) **CLAIM**

The ornamental design for a brush handle, as shown and described.

DESCRIPTION

FIG. 1 is a perspective view showing the top, left side and front of a first embodiment for a brush handle which forms my new design, the brush shown in broken lines in this and other figures being for environmental purposes only and forming no part of my design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a front elevational view thereof; and

FIG. 7 is a rear elevational view thereof;

FIG. 8 is a perspective view showing the top, left side and front of a second embodiment for a brush handle which forms my new design, the brush shown in broken lines in this and other figures being for environmental purposes only and forming no part of my design;

FIG. 9 is a top plan view thereof;

FIG. 10 is a left side elevational view thereof;

FIG. 11 is a bottom plan view thereof;

FIG. 12 is a right side elevational view thereof;

FIG. 13 is a front elevational view thereof; and,

FIG. 14 is a rear elevational view thereof.
